UNITED STATES PATENT OFFICE

159,709

TEXTILE FABRIC OR SIMILAR ARTICLE OF MANUFACTURE

Lou Appleton, New York, N. Y.

Application November 19, 1949, Serial No. 6,146

Term of patent 7 years

(Cl. D92—1)

To all whom it may concern:

Be it known that I, Lou Appleton, a citizen of the United States of America, and resident of the city, county, and State of New York, have invented a new, original, and ornamental Design for a Textile Fabric or Similar Article of Manufacture, of which the following is a specification, reference being had to the accompanying drawing, forming a part thereof,

Figures 1 and 1A, taken together and joined at lines A—A is a plan view of a textile fabric or similar article of manufacture, showing my new design. A complete design unit is contained between the broken lines and is repeated as indicated.

I claim:

The ornamental design for a textile fabric or similar article of manufacture, as shown and described.

LOU APPLETON.
